(57) CLAIM

The ornamental design for a guitarist gnome statue, as shown and described.

DESCRIPTION

The files of this patent contains at least one drawing/photograph executed in color. Copies of this patent with color drawings/photographs will be provided by the Office upon request and payment of the necessary fee. The colors form no part of the claimed design.

FIG. 1 is a front and right side perspective view of a guitarist gnome statue, showing my new design;
FIG. 2 is a front and left side perspective view thereof;
FIG. 3 is a top perspective view thereof;
FIG. 4 is a bottom perspective view thereof;
FIG. 5 is a front elevational view thereof;
FIG. 6 is a rear elevational view thereof;
FIG. 7 is left side elevational view thereof;
FIG. 8 is a right side elevational view thereof; and,
FIG. 9 is bottom plan view thereof.
